UNITED STATES PATENT OFFICE.

ANNETTA J. COLOMBOT, OF MADISON, CONNECTICUT.

HAT-FASTENER.

1,085,972.

Specification of Letters Patent. Patented Feb. 3, 1914.

Application filed February 18, 1913. Serial No. 749,253.

To all whom it may concern:

Be it known that I, ANNETTA J. COLOMBOT, citizen of the United States, residing at Madison, in the county of New Haven 5 and State of Connecticut, have invented certain new and useful Improvements in Hat-Fasteners, of which the following is a specification.

This invention relates to improvements 10 in devices for securing ladies' hats to the head, and has for one of its objects to improve the construction and increase the efficiency and utility of devices of this character.

Another object of the invention is to provide a simply constructed device including 15 a member adapted to resiliently engage the head of the wearer and with pins movable in opposite directions and carried by said 20 head engaging member and adapted to be projected by the wearer as the hat is placed in position upon the head to engage the hat and firmly hold the same.

Another object of the invention is to 25 provide a simply constructed device whereby a hat may be firmly held in position without disturbing the hair or thrusting pins or other devices through or into the hair of the wearer.

With these and other objects in view the invention consists in certain novel features of construction as hereinafter shown and described and then specifically pointed out 30 in the claims, and in the drawings illustrative of the preferred embodiment of the invention.

Figure 1 is a side elevation of the improved device in withdrawn position. Fig. 2 is a plan view of the parts shown in Fig. 40 1. Fig. 3 is an enlarged detail view illustrating the position of one of the pins in projected position.

Corresponding and like parts are referred to in the following description and indicated in all the views of the drawings by the same reference characters.

The improved device comprises a supporting member or plate 10 upon which the hat pins are movably mounted. Connected 45 at 11-12 to the under face of the member 10 are curved head engaging members 13-14, the head engaging members being of resilient material and engaging the head with sufficient force to prevent displacement 50 when in use. The members 13-14 will be curved to conform to the head of the wearer

and will be changed in form as required. By this simple means the improved device is effectually disposed in position upon the head, and requires no other fastening means 60 than its own resiliency.

Rising from the upper face of the member 10 at one side are guide devices 15 spaced apart and through which a rod 16, which constitutes one of the engaging pins 65 of the device, is mounted to slide, and provided at one end with a point 17 and held in withdrawn position by a spring 18. Connected to the plate 10 at the opposite side are other guide devices 19 through 70 which a rod 20, which constitutes the other hat engaging pin, is mounted to slide and with a terminal point 21 at one end and maintained yieldably in withdrawn position by a spring 22. 75

It will be noted by reference to Fig. 2 that the terminals of the plate 10 are formed oblique to the longitudinal plane of the plate with the guide members 15 at one end of the plate at one side and the guide members 19 at the opposite end of the plate at the opposite side so that the hat engaging pins 16-20 will be arranged with their points 17-21 extending in opposite directions. By this simple means the "throw" 80 85

or movement of the hat engaging pins is materially increased without increasing the length of the plate or member 10. A chain or like flexible member 23 is connected to the pin 16, preferably at its inner end, and 90 extends through apertures in the members 15 and thence over the outer face of the curved head engaging member 14 and terminates in a catch 24 adapted to be engaged over a button 25 upon the member 14, while 95 a similar chain or other flexible device 26 is connected to the pin 20, preferably at its inner end, and extends thence through apertures in the members 15 and terminates in a catch 27 adapted to engage over a button 28 100 upon the member 13. By this means it will be obvious that by applying a pulling force to the chains 23-26 the pins 16-20 may be projected in opposite directions and held in projected position by engaging the catches 105 24-27 respectively over the buttons 25-28. By this simple means when a hat is to be secured in position the catches 24-27 are released to permit the pins 16-20 to be automatically withdrawn through the action of 110 the springs 18-22. The members 13-14 are then placed over the head of the wearer

and the hat disposed upon the head and covering the member 10 and its attachments.

When the hat has been properly placed in position the flexible members 23-26 are drawn downwardly to cause the pins 16-20 to be projected in opposite directions and the points 17-24 engaged with the hat and the catches 24-25 engaged over the buttons 25-28 to hold the pins in their projected position.

When the hat is to be moved it is only necessary to release the catches 24-27 from the buttons 25-28 when the pins will be automatically withdrawn and release the hat. The members 13-14 with their attachments can then be readily removed.

The improved device is simple in construction, can be inexpensively manufactured and wholly of metal and increased or decreased in size to correspond to the hat.

Having thus described the invention, what is claimed is:

1. In a device of the class described, a head embracing device, hat engaging pins movably disposed relative to said head engaging device and movable in opposite directions, yieldable means for holding said pins withdrawn, means for projecting said pins against the resistance of said yieldable holding means, and means for holding said pin projecting means.

2. In a device of the class described, a head engaging device a hat engaging pin movably disposed relative to said head engaging device, yieldable means for holding said pin withdrawn, means for projecting said pin against the resistance of said yield-

able holding means, and means for detachably connecting said pin projecting means to said head engaging device. 40

3. In a device of the class described, a support, pins mounted to move in opposite directions relative to said support, springs operating to hold said pins yieldably in withdrawn position, means for moving said pins against the resistance of said springs, head engaging means carried by said support, and means for coupling said pin actuating means to said head engaging means. 45

4. In a device of the class described, a head engaging device, a hat engaging pin movably disposed relatively to said head engaging device, yieldable means for holding said pin withdrawn, means for projecting said pin against the resistance of said yieldable holding means, and means carried by said head engaging device for holding said pin projecting means. 50

5. In a device of the class described, a support, head engaging members connected to said support, guide devices carried by said support, supporting pins mounted to move in opposite directions through said guide devices, springs operating to hold said pins yieldably in withdrawn position, means for moving said pins through said guides against the resistance of said springs, and means for holding said pin moving means. 65

In testimony whereof I affix my signature in presence of two witnesses.

ANNETTA J. COLOMBOT. [L. S.]
